APPARATUS FOR CONTROLLING ROLL CONTOURS

Edward M. Chandler, Alcoa, Tenn., assignor to
Aluminum Company of America, Pittsburgh,
Pa., a corporation of Pennsylvania

Application April 8, 1931, Serial No. 528,635

2 Claims. (Cl. 80—41)

This invention relates to an improved apparatus for accurately controlling the contours of rolling mill rolls to retain the contours of rolls in the parallelism which is essential in the production of material of uniform gauge.

Deflection in the rolls and friction resulting from roll neck bearings and variations in the thickness of materials being rolled are for the most part responsible for the non-uniform contours in rolling mill rolls. To compensate for deflection, it is customary to employ crowned rolls, whereas the differences in the diameter of rolls because of unequal temperatures derived from friction causes are usually compensated for by applying heat or a cooling liquid to various portions of the rolls. These methods are open to considerable objection in that it is difficult to accurately determine the amount of crowning necessary, and to restrict temperature changes of rolls to the desired portions thereof.

It is the object of this invention to provide an improved apparatus whereby the contours of rolling mill rolls can be controlled through the application of pressure at predetermined portions of the rolls by pressure means disposed longitudinally thereof.

A further object of the invention is to provide an apparatus for accurately controlling the contours of rolling mill rolls by pressure means which will not interfere with the practical operation of the mill or produce any deleterious effect on the material produced.

In carrying out my invention, I may employ as a pressure means a sectional buff such as illustrated in the accompanying drawing, but it will be understood that this mechanism is by way of illustration, and other convenient means of accomplishing the results herein described may be employed.

In the drawing:

Fig. 1 represents a cross sectional elevation of a sectional buff as adapted to a rolling mill;

Fig. 2 represents a top plan view of the apparatus shown in Fig. 1;

Fig. 3 represents a view taken in the direction of the arrows III—III in Fig. 2.

The sectional buff is constructed from a plurality of individual pressure applying shoes or blocks arranged in a suitable housing supported between the housings of a rolling mill in a manner so that pressure may be applied at individual points across the width of the roll.

As shown in the drawing, the sectional buff comprises a channel shaped housing 10 within which are movably mounted a plurality of pres-

sure applying shoes or blocks 11 arcuately formed on their under surfaces to conform with the curved surface of the mill roll and embrace a buffing cloth 12 therebetween. The buffing cloth 12 is supported on a bar or rod 13 mounted in lugs 14 welded or otherwise attached to a flange of the housing 10 in such manner that the roll exerts a drag on the buffing cloth.

The blocks 11, which may be made of wood, gum, or of some other suitable material or composition, have roll engaging faces formed at oblique angles to their ends to eliminate any possibility of the formation of ridges on the roll surface, and are mounted upon the flexible spring steel strip 15.

Suitably attached, as by welding, to the upper surface or web of the channel housing 10 is a plate 16 upon which are formed bosses 17 equal in number to and disposed centrally over blocks 11. These bosses 17 are provided with threaded holes 20 through which pressure applying screws 18 are threaded. Aligning and securing pins 19, flanges 20 of which, in combination with the aforementioned spring steel plate 15, form a locking or securing means, are vertically mounted in blocks 11 and extend through the web of the housing channel 10 where they are provided with cotter pins 21 which limit the movement of the blocks 11 relative to the housing 10.

Interposed between the strip 15 and the underside of the channel web are individual pads 22 of a resilient material, which are backed up by the plates 23. These back-up plates and resilient pads are equal in number to the pressure applying blocks 11 and are aligned therewith by means of the pins 19.

The housing 10 with its various elements adjustably mounted therein is supported in proper relationship with the rolling mill roll by means of angle brackets 24, shown to best advantage in Fig. 3, which are attached, as by bolts 32, to the riders 33 in which the roll bearings are supported. A rigid connection between the brackets 24 and the sectional buff housing 10 is accomplished by means of the knurled headed bolts 25 threaded through the brackets 24. These bolts are of the shouldered type having reduced diameter portions 26 which project through slots 27 formed in the upper portion or web of the housing 10. Suitable washers 28 and nuts 29 threaded on the reduced diameter portions of bolts 25 complete the connection. The cut away portions 30 in the housing flange allow nuts 29 to be readily applied, and the lugs 31, extending from the brackets 24 projecting into the housing 10 and bearing against

the inner surface of the flange, preclude the possibility of the assembled sectional buff twisting about the bolts 25.

- From the foregoing description, it will be understood that by manipulation of the individual pressure applying screws 18, pressure may be applied in varying degrees to separate portions of the roll face through the medium of the back-up plates 23, the resilient pads 22, and the blocks 11. 5
- 10 The back-up plates serve to distribute the pressure over the entire surface of each individual block 11 and the resilient pads 22 insure a yielding contact of the blocks 11 with the buffing cloth 12 in contact with the roll surface.
- 15 In practical operation, the contour of the roll, to which the sectional buff has been adapted, can be accurately controlled by increasing or decreasing the pressure at desired points over the roll surface. By these pressure changes, the friction 10 of the buff on the roll is either increased or decreased, with the result that the roll temperature and, consequently, the roll contour may be accurately controlled. Although the buff has been shown as applied to one roll, it is quite applicable 20 to all of the rolls contained in the mill.
- 25 While my improved apparatus for controlling the contours of rolling mill rolls has been illustrated and described with reference to a particular device, it is to be understood that the invention is not to be limited thereto as the same may be practiced in various other ways without departing from the spirit and scope of the appended claims. 30

What I claim is:

1. In a roll contour-controlling apparatus, a housing adjustably mounted adjacent a rolling mill roll, a buffing cloth supported by said housing in contact with said roll, a plurality of pressure-applying shoes disposed within said housing, said pressure-applying shoes having an arcuately formed face in contact with said buffing cloth, a flexible steel strip attached to said pressure-applying shoes, means for aligning and movably securing said pressure-applying shoes relative to said housing and roll, and independent means for controlling the pressure exerted by each pressure-applying shoe. 10

2. In a roll contour-controlling apparatus, a 15 plurality of individual pressure-applying shoes, a flexible steel strip attached to one face of said pressure-applying shoes, the opposite face thereof being curved to conform with a roll in a rolling mill, a housing for said pressure-applying shoes, 20 aligning and securing pins extending from said pressure-applying shoes through said housing, said pins being provided with stop elements limiting the movement of the pressure-applying shoes relative to the housing, independent pressure-applying means extending into said housing, resilient pads and rigid pressure plates disposed between said independent pressure-applying means and said pressure-applying shoes, said independent pressure-applying means providing 25 means for applying a variable pressure along the length of a rolling mill roll. 30

EDWARD M. CHANDLER.
